UNITED STATES PATENT OFFICE.

PERLEY R. GLASS, OF QUINCY, MASSACHUSETTS.

EYELETING-MACHINE.

SPECIFICATION forming part of Letters Patent No. 636,035, dated October 31, 1899.

Application filed September 5, 1899. Serial No. 729,497. (No model.)

To all whom it may concern:

Be it known that I, PERLEY R. GLASS, of Quincy, county of Norfolk, and State of Massachusetts, have invented an Improvement in Eyeleting-Machines, of which the following description, in connection with the accompanying drawings, is a specification, like letters on the drawings representing like parts.

The present invention relates to an eyeletting-machine, and is embodied in a machine for setting eyelets, rivets, and the like, especially eyelets, the machine being mainly intended for work on leather stock, especially shoe-uppers. In a machine of this class it is necessary in order to obtain good results to employ a tubular punch coöperating with a flat anvil, since no other kind of a punch will properly cut holes in leather or retain its cutting edge when used with this material for any length of time.

It is the object of the present invention to simplify the construction of the machine, so as to obtain the greatest possible rapidity and efficiency, and to this end the machine embodying the invention is provided with a reciprocating tubular punch having an annular clenching-flange from which it projects, so as to combine in one tool a punch and setting device which is adapted first to punch the material and then to coöperate with another reciprocating setting device adapted to pick up an eyelet and present the same to the clenching portion of the punch, thus inserting the eyelet in the previously-punched hole and setting or clenching the same.

In machines as heretofore commonly constructed, in which a tubular punch adapted to operate properly upon leather stock has been employed, it has been found necessary to utilize a pair of setting devices, both operated independently of the punch itself. In accordance with the present invention, however, this multiplicity of tools is dispensed with, thereby greatly simplifying the construction and increasing the rapidity of operation.

The punch employed is shown as smaller in diameter at its cutting edge than the eyelet which is to be operated upon, so that in the setting operation the tubular cutting portion of the punch will readily enter the eyelet to prevent the cutting edge from injuring or

being injured by the edge of the eyelet. To insure, therefore, that the eyelet will be properly guided into the hole or opening in the stock, the machine is provided with means independent of the punch and anvil, or "coöperating punching devices," as they may be called, for forcing the punch through the material after the actual punching or cutting operation is completed, so that the said punch will project beyond the surface of the material before the eyelet is presented thereto. It is desirable, moreover, that the outer surface of the tubular punching projection should be tapered somewhat, so that as the said punch is forced through the material the hole therein will be slightly enlarged, while the tapering projection will engage the edge of the eyelet as the punch projects into the same and guide the said edge between the exterior of the punch and the materials surrounding the same. In this way the eyelet presented by the independent setting device is properly guided and positioned, and a slight inaccuracy in the original positioning of the eyelet on the setting device will not result in crushing the eyelet or damaging the punch, as would be the case if a similar imperfection existed in a machine which did not have a tapered punch or a machine in which the diameter of the punch was as nearly as possible equal to the interior diameter of the eyelet, so that the hole originally punched might be as nearly equal as possible in diameter to the diameter of the eyelet itself.

The invention further relates to novel details of construction and arrangement, which will be more fully described hereinafter.

Figure 1 is a front elevation of a machine embodying the invention; Fig. 2, a vertical section of the same; Fig. 3, a detail in section on the line x^3 of Fig. 2; Fig. 4, a similar detail in section on the line x^4 of Fig. 2; Fig. 5, a section on planes transverse to that of Fig. 2, the upper portion of said section being taken on a line at the rear of the punch-frame and the lower portion being taken on a line farther back and just in front of the feed-operating cam; and Figs. 6, 7, 8, and 9 are enlarged sectional details of the combined punch and setting-tool and the coöperating setting device, together with a portion of the feed-table, to illustrate the successive

steps in the operation, especially with a view to showing the manner of inserting and clinching the eyelet.

The machine embodying the invention comprises the tubular punch *a*, shown as externally tapered and provided with the annular clinching-surface *a*², the coöperating setting device *b*, shown as provided with a spring-finger *b*², and the eyelet-feed chute *c*, adapted to receive eyelets from the hopper *c*² and to be moved into and out of the path of the setting device *b* in the usual way, so as to successively present the eyelets to the finger *b*² prior to the setting operation. The punch *a* coöperates in the punching operation with a suitable anvil or support for the material, the punch and anvil thus constituting coöperating punching members, the said anvil *A* being indicated in Fig. 6, in which the punch *a* is shown in the position assumed at the end of the punching operation. It is necessary, therefore, prior to the setting operation that a movement of one of the said punching members relative to the other should take place in order to permit the setting device *b* to move toward the clinching-surface *a*² and coöperate therewith in the setting operation.

As herein shown, the punch *a* is arranged to have a lateral movement, the same lateral movement which brings the punch into a position to be met by the setting device also serving to feed the material after the same has been punched. To this end the punch is mounted in a laterally-movable frame *a*³, shown as capable of sliding on the guide-rod *a*⁴, supported in lugs *B*, formed in the front part of the frame of the machine. The punch is capable of a reciprocating longitudinal movement within said frame, as will be hereinafter described, so as to perform the actual punching operation, but is moved with the frame between successive punching operations, so as to feed the material and coöperate in completing the setting or clinching of the eyelet.

To produce the lateral movement of the frame *a*³, the said frame is connected, in accordance with the present invention, with an oscillating member *d*, provided with a radial arm *d*², which arm is connected by a universal joint with the punch-frame *a*³, so as to compensate for the difference between the curved and rectilinear movements of the two parts. As herein shown, the said arm *d*² is provided with a channel *d*³, the walls of which engage a sliding block *a*⁵, pivotally connected with the frame *a*³, the said block being herein shown as held in position with relation to said frame by means of a screw *a*⁶, having a rounded head *a*⁷, which constitutes a bearing for the said block. In the oscillation of the said member *d*, therefore, the punch-frame will be laterally reciprocated, it being essential that the said punch-frame should come to rest at one end of its reciprocating movement in such a po-

sition that the punch will be in line with the setting device *b* in order to coöperate therewith in setting the eyelet. The member *d*⁷⁰ is oscillated in response to the rotation of the main shaft of the machine, as will be described, and the arm *d*² is shown as adjustably connected to said member, so that the exact position of the punch at the end of its feed movement may be properly arranged for. As herein shown, the said arm *d*² is provided with a hub or collar *d*³⁰, having ears or lugs *d*⁴, each of which contains an adjusting-screw *d*⁵, which coöperates with a tongue or projection *d*⁶ from the member *d*. The distance between the lugs *d*⁴ is somewhat greater than the thickness of the tongue *d*⁶, so that by turning one or the other of the screws the position of the arm relative to the member *d*⁸⁵ may be determined, as best shown in Fig. 3.

In the construction shown the lateral movement of the punch is utilized to feed the material so as to produce a completely automatic setting operation, the punch first descending to cut the material, then moving laterally to transfer the same to the setting device, and then returning to punch another opening prior to the next setting operation. It is desirable, however, to provide the machine with means for varying the extent of the feed movement in case it is necessary to set part of the eyelets at one distance apart and other eyelets in the same line at different distances apart. This is accomplished by varying the lateral or feed movement of the punch, and in accordance with the present invention the member *d*, which is shown as a sleeve having a bearing on the shaft *e*, which produces the vertical reciprocating movement of the punch, is provided with an arm *d*⁷, projecting radially from said member and being connected with an actuating member *d*⁸, which receives a reciprocating movement from a cam *d*⁹ on the main shaft *C* of the machine, which is adapted to be continually rotated during the operation of the machine. The said cam *d*⁹ coöperates with engaging surfaces *d*¹⁰, formed in a frame *d*¹², connected with the member *d*⁸, the said member also being provided with fingers or projections *d*¹³, Fig. 4, constituting a fork embracing the shaft *C*, so as to keep the frame *d*¹² in proper position with relation to the cam *d*⁹. Thus while the movement of the member *d*⁸ is mainly a reciprocating movement said member is free to turn slightly with relation to the shaft *C*, so as to properly follow the movement of the arm *d*⁷, with which it is connected. Thus in the operation of the machine the rotation of the main shaft *C* through the action of the cam *d*⁹, the connecting member *d*⁸, and the arm *d*⁷ will oscillate the member *d* in accordance with the shape of the cam *d*⁹, so as to produce the necessary movement thereof to feed the material and return the punch to its normal position. It is obvious, however, that the extent of such movement will be varied by shifting the point of connection between the arm *d*⁷ and the con-

necting member d^8 toward or from the axis of oscillation of the member d , since the nearer the said point of connection is to the said axis the longer will be the movement of the said member d . In order that the point of connection may be thus shifted readily by the attendant even while the machine is in operation, the arm d^8 is shown as connected, by means of a link d^{14} , with an actuating device, shown as an elbow-lever d^{15} , pivoted at d^{16} , one arm of said elbow-lever being connected at d^{17} with a suitable actuating device, such as a treadle. (Not herein shown.) Taking the parts, therefore, in the position shown in Fig. 5, if the point d^{17} is moved downward it is obvious that the connecting member d^8 will be carried toward the axis of the member d , thereby lengthening the feed movement. The amount that the feed movement is lengthened may be determined by the stops d^{18} , one at each side of one arm of the elbow-lever d^{15} , the said stops being shown as screw-threaded in suitable lugs and held in position by lock-nuts d^{19} , so that they are easily adjustable to vary the extent of movement of the elbow-lever and the consequent variation in the feed movement of the punch.

It is of course necessary that the punch should always be arrested at the end of its feed movement in such position that it will be directly in line with the lower setting device, so as to receive the eyelet therefrom and coöperate therewith in the setting operation. To this end the member d^8 is connected with the arm d^7 by means of a stud d^{20} , arranged to engage the walls of a slot d^{21} in the member d^7 , and the said walls of the said slot d^{21} are curved upon the arc of a circle struck from the axis of the shaft C when the said arm d^7 is in such a position that the punch is directly in line with the lower set. It is obvious, therefore, that no matter to what position the stud d^{20} is shifted there will be no variation in the position of the punch at this point of its travel, so that no matter what the feed movement may be the said punch will always be arrested in the proper position with relation to the setting device. In other words, the extent of feed movement is varied by initially varying the extent of backward movement of the punch, so that said punch may be caused to engage the material at varying points on the punch-block, while it always moves said material to such a position that the punched hole is in line with the lower set, which is laterally stationary. The extent of feed movement, therefore, is equal to the distance between the point where the material is punched and the point where the eyelet is set, and the said distance is variable in accordance with the variation in the initial rear movement of the punch.

The reciprocating movement of the punch is produced, as has been stated, through the agency of the shaft e , which is arranged to be continuously rotated, and is provided with a cam e^2 , which coöperates with engaging

surfaces e^3 , formed in a block e^4 , which is connected with the punch a . As shown, the said surfaces e^3 constitute an elongated channel, 70 so that the block is capable of movement along the cam to permit the lateral movement of the punch, and is also adapted to be moved to reciprocate the punch in response to the rotation of the said cam. As best shown in Fig. 1, the shape of the cam is such as to permit the punch to dwell at the end of its movement toward the anvil, so as to remain in this position until after the setting operation is completed. 80

The shaft e is herein shown as rotated by means of a pair of eccentrics e^5 , each of which has an eccentric-strap e^6 connected by a rod e^7 with an eccentric-strap e^8 upon an eccentric e^9 , mounted on the shaft C . The two eccentrics on the same shaft are set so that one is about a quarter of a turn in advance of the other in order that one pair of eccentric-straps will be in operative position when the other pair are on the dead-center. 90

Since there must be a lateral movement of one of the coöoperating punching members relative to the other prior to the setting operation in order that the combined punch and setting-tool and the other setting-tool may come together, it is necessary that the punch and anvil, which are forced into firm engagement with each other in the punching operation, should be freed from each other in order that the lateral movement of one of the said parts may take place freely and without friction, since otherwise both the punch and the anvil would be rapidly worn out and the machine would not operate properly. As herein shown, the anvil A is so arranged as to have a slight movement away from the punch immediately after the punching operation, the said anvil being shown as pivoted at A^2 and supported upon an eccentric A^3 , which is arranged to be rotated in any suitable or usual way, as by beveled gears A^4 , A^5 , A^6 , and A^7 , the last-named gear being upon the main driving-shaft C . The operation is clearly indicated in Figs. 6, 7, 8, and 9, Fig. 6 showing the position of the anvil at the end of the punching operation and the other figures the position of the anvil immediately after the punching operation is completed, but prior to the movement which takes place in order to permit the punch and setting device to come together. The slight downward movement of the anvil prior to the lateral feed movement of the punch separates the coöoperating punching members, so that the lateral movement may be freely accomplished, it being obvious, 125 however, that the parts may be so timed that these movements may begin almost simultaneously, thereby insuring great rapidity of operation. It will be seen, however, from Fig. 6 that at the end of the punching operation the cutting edge of the punch is on a level with the lower surface of the material and that it does not project beyond the surface of the material at all. It is desirable, 130

however, that the punch should be somewhat smaller than the edge of the eyelet which is to be set in order to obviate all liability that the edge of the punch and the edge of the eyelet may come in contact with each other, and thereby injure or destroy one or both, and in any event prevent the proper setting of the eyelet in that particular hole. With the punch smaller than the eyelet, however, and flush with the surface of the material the eyelet instead of entering the opening in the material would come in contact with the uncut material around the punch if the material were allowed to remain in the position shown in Fig. 6 during the setting operation. To insure the proper setting, therefore, and to assist in guiding the eyelet into the opening, the machine is provided with means for forcing the punch completely through the material until it projects beyond the surface of the same after the punching operation is completed and prior to the setting operation. As herein shown, this is accomplished by providing the anvil A or any suitable portion of the feed-table with projecting fingers A⁸. (Shown on a large scale in Figs. 6, 7, 8, and 9.) These fingers project upward beyond the end of the punch, one at each side thereof, as the said punch travels laterally from the position shown in Fig. 6 to the position shown in Figs. 8 and 9. The material carried along by the punch, therefore, will come in contact with the upper surfaces of the fingers A⁸ and will be forced upward onto the punch, as shown in Fig. 7, so that when the said punch is in the position to coöperate with the setting device it will project wholly through the material and beyond the lower surface of the same. This is best shown in Fig. 8, in which it will be seen that the punch projects into the eyelet E until the edge of the eyelet engages the tapered walls of the punch and is thereby guided into the hole made in the material, which is enlarged sufficiently to properly receive the eyelet, so that the said eyelet cannot fail to enter and be upset or clenched, as shown in Fig. 9.

It is obvious that the means for forcing the punch through the material after the punching operation may be readily modified, and it is not intended, therefore, to limit the invention to the particular means herein shown and described.

The lower set b is carried by a vertical reciprocating rod b³, adapted to be reciprocated by means of a wrist-pin C² upon a disk C³, formed upon the main shaft C. The said wrist-pin C² enters an opening in a block b⁴, capable of sliding in a cross-head b⁵, suitably connected with the rod b³, so as to produce a regular reciprocating movement of the setting device b. The said setting device b is vertically adjustable with relation to the rod b³ by means of a screw-threaded adjusting member b⁶, which bears against the end of a shell b⁷, which in turn engages the end portion of the set b, the upper portion of said set being engaged

by an annular cap or nut b⁸. In adjusting the set the nut b⁸ is turned to such a position as to determine the proper position of the set, and the adjusting member b⁶ is then screwed up until the parts are locked, as will be easily understood by reference to Fig. 2.

The finger b² is acted upon by a spring b⁹, contained in the shell b⁷. The said finger, which is adapted to pick up an eyelet from the chute c in the usual way, is tapered, so as not to come in contact with the edge of the punch, and will usually be depressed by contact with the piece of leather last punched out of the material.

To retain the material in position after the setting operation has taken place and prior to the return movement of the punch, the machine is provided with a gripper member f, 85 spring-pressed against the feed table or anvil, as shown, and connected with a vertically movable rod f², acted upon by an arm f³, pivoted at f⁴ and operated by a cam f⁵ on the shaft C. The parts are so timed that the gripper descends and engages the material just after the feed movement is completed and remains in engagement therewith as the punch and setting device move apart. To enable the operator to insert the material prior to starting the machine, the gripper member is also arranged to be acted upon by a lever f⁶, connected with a suitable treadle or actuating device. (Not shown.)

The feed-chute c may be reciprocated or oscillated in any suitable or usual way to present the eyelets to the setting device and is herein shown as oscillated by means of a cam c², acting on the forked extremity c⁴ of an elbow-lever c⁵, suitably connected with an oscillating frame which carries the said eyelet-chute and feed-hopper, the construction and arrangement of which need not be further described, since they form no part of the present invention.

It is to be understood that while the punch has been hereinbefore described as laterally movable, constituting also the feed member of the machine, such a construction is not essential to the invention, since other means for feeding the material may be employed, while it is obvious that other means might also be employed for laterally separating the punch and anvil to permit the setting device to come in line with the said punch.

It is further obvious that many other modifications might be made in the specific construction and arrangement of the machine, and it is not intended, therefore, to limit the invention to the particular embodiment thereof which has been herein shown and described.

I claim—

1. In an eyeleting-machine, the combination with a tubular punch provided with an annular clenching-surface; of an anvil into contact with which said punch is adapted to move in the punching operation; means for separating said punch from said anvil after

the punching operation by a lateral movement of one of said parts; means for forcing the punch farther through the material after the punch has left the anvil; a reciprocating setting device adapted to coöperate with said annular clenching-surface; and means for automatically supplying said setting device with eyelets.

2. In a machine for setting eyelets, rivets 10 and the like, the tubular punch provided with an annular clenching-surface; means for producing a longitudinal and lateral movement thereof to punch and feed the material; a setting device coöperating with said punch;

15 and means for forcing the punch farther through the material during such lateral movement, so that the punch projects beyond the surface of the material prior to the operation of said setting device.

20 3. In a machine for setting eyelets, rivets and the like, the tubular punch provided with an annular clenching-surface; means for producing a longitudinal and lateral movement thereof to punch and feed the material;

25 a setting device coöperating with said punch; means for varying the extent of the lateral movement of the punch to vary the feed movement of the material; and means for forcing the punch farther through the mate-

30 rial during such lateral movement so that the punch projects beyond the surface of the material prior to the operation of said setting device.

4. In a machine for setting eyelets, rivets 35 and the like, a tubular tapered punch provided with an annular cutting edge smaller in diameter than the eyelet to be set and an annular clenching-surface; means for producing a longitudinal and lateral movement

40 thereof to punch and feed the material; a setting device coöperating with said punch; means for presenting the article to be inserted in the material to said setting device; and means for forcing the punch farther through

45 the material during such lateral movement, so that the punch will project beyond the surface of the material prior to the operation of said setting device.

5. In a machine for setting eyelets, rivets 50 and the like, a tubular punch provided with an annular clenching-surface; means for producing a longitudinal and lateral movement thereof to punch and feed the material; a setting device coöperating with said punch;

55 means for forcing the punch through the material so that it projects beyond the surface thereof prior to the setting operation; and independent means for holding the material after the lateral movement of the punch has

60 taken place to feed the same.

6. In a machine for setting eyelets, rivets and the like, a tubular punch; means for producing a longitudinal and lateral movement thereof to punch and feed the material, said

65 punch being tapered and provided with an annular clenching-surface; means for forcing the material onto said punch after the

punching operation so that the punch projects beyond the surface of the material; a setting device coöperating with said punch; 70 means for presenting the article to be inserted in the material to said setting device; a gripper member adapted to hold the material on its support during the punching and setting operations; and means for separating 75 said gripper member from said support during the lateral movement of the punch which feeds the material.

7. In a machine for setting eyelets, rivets 80 and the like, a tubular punch; means for producing a longitudinal and lateral movement thereof to punch and feed the material, said punch being tapered and provided with an annular clenching-surface; means for forcing the material onto said punch after the 85 punching operation so that the punch projects beyond the surface of the material; a setting device coöperating with said punch;

85 means for presenting the article to be inserted in the material to said setting device; a gripper member adapted to hold the material on its support during the punching and setting operations; means for separating said gripper member from said support during the lateral movement of the punch which feeds 95 the material; and independent means for operating said gripper member to insert the material.

8. In an eyeleting-machine, the combination 100 with the tubular punch provided with a clenching portion; of means for producing a reciprocating longitudinal movement thereof to force the cutting edge into the material; means for producing a lateral movement thereof; means for forcing the material onto 105 the punch until said punch projects beyond the surface thereof; connecting mechanism whereby the longitudinal and lateral movements of the punch are produced to punch and feed the material; and a setting device 110 to coöperate with the clenching portion of the punch.

9. In an eyeleting-machine, the combination 115 with the tubular punch provided with a clenching portion; of means for producing a reciprocating longitudinal movement thereof;

means for producing a lateral movement thereof; connecting mechanism whereby the longitudinal and lateral movements of the punch are caused to punch and feed the material; means for varying the extent of the lateral movement of the punch; a setting device to coöperate with the clenching portion of the punch; and means for causing the punch to project through the material and 125 beyond the surface thereof prior to the setting operation.

10. The combination with the punch; of the laterally-movable punch-guide frame; a laterally-stationary setting device; an oscillating member coöperating with said frame; an arm projecting radially from said oscillating member; a slot or channel in said rod the walls of which follow an arc struck from the

axis of a suitable driving-shaft when said arm is in such a position that the punch is in line with the setting device; a rod having a projection coacting with the walls of said slot, 5 the said rod also being provided with a forked guide coöperating with said driving-shaft; a cam on said driving-shaft coacting with said rod to produce a substantial reciprocating movement thereof; and independent means 10 for laterally moving said rod to vary the point of connection between the same and said radial arm, as set forth.

11. The combination with the tubular punch projecting from and surrounded by an annular clenching-surface; of an anvil to coöperate with said punch in the punching operation; means for separating the punch and anvil after the punching operation; means for subsequently forcing said punch through the 20 material until it projects beyond the surface thereof; and a setting device adapted to present an eyelet to said punch which guides the eyelet into the hole in the material and coöperates with the setting device in the clenching 25 of said eyelet.

12. In an eyeleting-machine, a tubular tapered punch provided with and projecting from an annular clenching-flange; the cutting edge of the punch being smaller in diameter than the eyelet to be set and the outer surface of the punch beyond the cutting edge increasing to a diameter equal to or greater than that of the eyelet; an anvil or support for the material in conjunction with which support 35 the cutting edge of the punch is caused

to perforate the material; separate means for forcing the punch through the material after the perforation is made so that the tapered end of the punch will project beyond the surface of the material; a setting device adapted 40 to present an eyelet to said projecting punch so that the latter enters the eyelet and guides it into the perforation, said setting device then coöperating with the clenching portion of the punch to set the eyelet; and connecting mechanism whereby said parts automatically coöperate to punch the material and set the eyelet. 45

13. In an eyeleting-machine, the combination with the punch adapted to move laterally 50 to feed the material along a suitable support; of one or more fingers projecting from said support to engage the material and press it onto said punch, substantially as described.

14. In an eyeleting-machine, the combination with the punch adapted to move laterally 55 to feed the material; of an anvil to coöperate with said punch in the punching operation; means for separating the punch and anvil prior to the lateral feed movement of said punch; and means for forcing the material onto said punch in the lateral movement thereof, for the purpose set forth.

In testimony whereof I have signed my name to this specification in the presence of 65 two subscribing witnesses.
